CLAIM

The ornamental design for a pill organizer case, as shown and described.

DESCRIPTION

FIG. 1 is a front, top, left side perspective view for a pill organizer case, showing my new design;
 FIG. 2 is a front elevational view of FIG. 1 thereof, the rear elevational view being a mirror image;
 FIG. 3 is a left side elevational view of FIG. 1 thereof;
 FIG. 4 is a right side elevational view of FIG. 1 thereof;
 FIG. 5 is a top plan view of FIG. 1 thereof;
 FIG. 6 is a bottom plan view of FIG. 1 thereof;
 FIG. 7 is an exploded front, top, left side perspective of the pill organizer case of FIG. 1 thereof, showing the lid and base; and,
 FIG. 8 is an exploded front, bottom, right side perspective of the pill organizer case of FIG. 1 thereof, showing the lid and base.
